Patented June 6, 1967

207,895

ASH TRAY

Oliver J. Bacott, 4407 Springdale,
Berkeley, Mo. 63134

Filed Feb. 7, 1966, Ser. No. 936

Term of patent 14 years

(Cl. D85—2)

FIG. 1.

FIG. 2.

FIG. 3.

FIG. 4.

FIG. 5.

FIG. 1 is a front elevational view in elevation of an ash tray showing my new design;

FIG. 2 is a section on line 2—2 of FIG. 1;

FIG. 3 is a plan view of the ash tray;

FIG. 4 is a side elevational view;

FIG. 5 is a bottom view of the ash tray.

I claim:

The ornamental design for an ash tray, substantially as shown.
